UNITED STATES PATENT OFFICE.

JAMES N. PARRAHM, OF KANSAS CITY, MISSOURI.

TOOL FOR SHOEMAKERS.

1,206,585.

Specification of Letters Patent. Patented Nov. 28, 1916.

Application filed January 6, 1916. Serial No. 70,630.

To all whom it may concern:

Be it known that I, JAMES N. PARRAHM, a citizen of the United States, residing at Kansas City, in the county of Jackson and ⁵ State of Missouri, have invented certain new and useful Improvements in Tools for Shoemakers, of which the following is a specification.

This invention relates to improvements ¹⁰ in tools for shoemakers, one object of the invention being the provision of a tool the handle of which is provided with means for straightening or smoothing out the welt.

Another object of the present invention is ¹⁵ the provision of a shoemaker's tool which is simple, durable and inexpensive in construction and thoroughly efficient and practical in use. In the accompanying drawings: Figure 1, is a perspective view of the complete tool. Fig. 2 is a section longitudinally of the handle. Fig. 3 is a detail ²⁰ transverse sectional view through the handle of the tool.

Referring to the drawings, the number ²⁵ 5 designates the handle, which is provided with the relatively narrow blade receiving slot 6 in one end thereof. The blade 7, is

provided with the reduced end 8, for insertion in the slot 6, such reduced end being further provided with an aperture 9, for the ³⁰ reception of the reduced end 10', of the locking screw 10, insertible through the threaded bore 11, of the handle. This bore is open from one side only, and the screw projects slightly beyond the center of the handle ³⁵ when engaging the blade and locking the same against longitudinal movement.

The butt end 12 of the handle is tapered and is fitted with the V-shaped in longitudinal section metal smoothing or straightening member 13, which is held in place by the rivet 14. The lower edges of the member 13, are rounded, and for some distance they are closed, thus preventing any rough or cutting ⁴⁰ edges at this point. ⁴⁵

What I claim, as new, is:—

A shoemaker's tool, including a handle having a tapered end, and a metal cap therefor V-shaped in longitudinal section fitting upon the tapered end, and forming a smoothing and burnishing implement. ⁵⁰

In testimony whereof I affix my signature.

JAMES N. PARRAHM.
